UNITED STATES PATENT OFFICE

2,349,195

METAL DOOR CONSTRUCTION

James F. Peele, Richmond, Ind.

Application February 5, 1942, Serial No. 429,596

1 Claim. (Cl. 189—46)

The principal object of the invention is the construction of a door comprised of preformed members whereby the same is easily and quickly assembled.

A second object of the invention is the provision of a door constructed of a plurality of preformed members and having a fire-retarding member enclosed therein.

A third object of the invention is the provision of a metal door which is comprised of a plurality of preformed members nested together and having an insulating member located therein, and with the assembled door being highly resistant to extremely high temperatures.

A further object of the invention is the provision of a fire-resisting door which will meet the most exacting requirements of safety ordinances, which is economical to manufacture, which is simple of construction, and for which maintenance is substantially nil.

Other objects and advantages of the invention will suggest themselves in the course of the following description, and that which is new will be pointed out in the appended claim.

The most satisfactory means of carrying out the principles of the invention in a practical, economical, and efficient manner is shown in the accompanying two sheets of drawings in which:

Figure 1 is an elevation of a door comprised of a plurality of preformed members in accordance with the principles of the invention.

Figure 2 is a detail section through the door, taken on line 2—2 of Figure 1.

Figure 3 is an enlarged detail section through one edge of the door, taken on line 3—3 of Figure 1.

Figure 4 is an enlarged detail section through the opposite edge of the door, taken on line 4—4 of Figure 1.

Figure 5 is an enlarged detail section taken on line 5—5 of Figure 1 showing the method of securing the preformed members of one face of the door to the nested-together portions of the preformed members forming the opposite face of the door.

Figure 6 is a detail vertical section, taken on line 6—6 of Figure 1, through the top edge of the door showing the method of providing lateral rigidity thereto.

Figure 7 is a detail section taken on line 7—7 of Figure 1 showing the stiffening members provided in the lower edge of the door.

Figure 8 is a detail section through one of the preformed members.

Like characters designate like parts throughout the several views.

In order that the construction and the advantages of the invention may be more fully understood and appreciated, I will now take up a detailed description thereof, in which I will set forth the same as fully and as comprehensively as I may.

Referring now to the drawings I designates 10 preformed intermediate members, the major portions of which form the faces of the door. Each of the members 1 has a portion 2 formed along one edge thereof and with a portion 3 being formed along the opposite edge. It will be noted the portion 2 of one member 1 is adapted 15 to nest with the portion 3 of the adjacent member 1 as shown in Figure 5.

One edge of the door is formed by the members 4 and 6 as shown in Figure 3. Member 4 20 has a portion 2 formed along one edge which is adapted to nest into the portion 3 of the adjacent intermediate member, with the other edge 5 being formed at substantially right angles to the member 4 and forming one of the vertical 25 edges of the door. Member 6 has a portion 2 formed along one edge thereof which is adapted to nest with the adjacent portion 3 of an intermediate member 1. The opposite edge 7 of the member 6 is formed at substantially right angles 30 to the member and lies against the inner surface of the portion 5. A flange 8 is formed on the edge portion 7, the purpose of which will be hereinafter set forth.

The opposite edge of the door, as shown in 35 Figure 4, is comprised of the members 9 and 10. Member 9 has the portion 3 formed along one edge with the portion 3 being adapted to fit around the edge 2 of the adjacent intermediate member 1. The opposite edge 11 of the member 40 9 is formed at substantially right angles thereto and forms the edge of the door. Member 10 has the portion 3 formed along one of its edges and is adapted to fit around and nest with the portion 2 of the adjacent intermediate member. A portion 12 is formed along the opposite edge of 45 the member 10 with the portion 12 being adapted to lie against the inner surface of the edge 11. The flange 13 is formed on the portion 12, the purpose of which will be hereinafter set forth.

50 It will be noted from the drawings that each side of the door is assembled independently of the other side. One side of the door is formed by laying the members together so their edges will nest together. A sheet of asbestos 14 or other fire-resistant material is then laid in the as-

55

sembled side of the door, after which the second side of the door is assembled by laying the members on the sheet 14 with their respective edges being nested together and with the portions 7 and 12 fitting within their companion members 5 and 11 respectively as shown in Figures 3 and 4. The flanges 8 and 13 lay against the edges of the sheet 14 and provide means of maintaining the edges of the sheet in their respective positions.

After the sides of the doors have been laid together with the sheet 14 being positioned therebetween, screws 16 and 17 are threaded into the respective flanges 8 and 13 with screws 16 securing the members 4 and 6 together and clamping the edge 14' between the member 4 and the flange 8 and with screws 17 securing members 9 and 10 together and clamping edge 14'' between member 9 and flange 13, all as shown in Figures 3 and 4. Screws 15 are extended through the side members 1 and through the sheet 14 and are threaded through the portions 2' and 3' of the members 2 and 3 respectively. After the members are assembled as above set forth the edges of members 5 and 11 are welded to the respective companion members 7 and 12 at points designated by 18 and 19.

The portions 2 and 3 are cut shorter at each end than the members 1, 4, 6, 9, and 10 to permit the insertion of top stiffening channel members 20 and 21 and bottom stiffening channel members 22 and 23. Channel 20 is inserted between the upper ends of the members 1 and welded or otherwise suitably secured therethrough after which channel 21 is inserted in channel 20 in an inverted

position as shown in Figure 6. Channel 21 is securely welded to channel 20 at the points designated by numerals 24. The bottom channels 22 and 23 are assembled into the door construction in a similar manner to that described above for channels 20 and 21 and are welded similarly at points designated by numerals 25 as shown in Figure 7.

It will be noted that the vertically extending members 2, 3, 5, 7, 11, and 12 provide rigidity longitudinally of the door with members 20, 21, 22, and 23 providing rigidity laterally of the door. The sheet 14, being of heat and fire-resisting material, retards the transmission of excessive heat through the thickness of the door.

It is to be understood that I am not to be limited to the exact arrangement of the members as shown but that minor changes may be made therein insofar as the changes may fall within the scope of the appended claim.

Having now fully shown and described the invention, what I claim, and desire to secure by Letters Patent of the United States, is:

In a metal door having a pair of opposed sides, each side being composed of preformed sections having inwardly-projecting nesting edges, a sheet of fire-resistant material positioned between the sides and secured in fixed position between the nesting members of one side and the inner face of the opposite side, and with screws extending through each side into the nesting members of the opposite side and securing the sheet of fire-resistant material therebetween.

JAMES F. PEELLE.
